Attorney

UNITED STATES PATENT OFFICE.

SHERWOOD HINDS, OF RICHMOND HEIGHTS, MISSOURI, ASSIGNOR TO ST. LOUIS PUMP & EQUIPMENT COMPANY, OF ST. LOUIS, MISSOURI, A CORPORATION OF MISSOURI.

VALVE.

Application filed February 25, 1922. Serial No. 539,301.

To all whom it may concern:

Be it known that I, SHERWOOD HINDS, a citizen of the United States, and a resident of Richmond Heights, St. Louis County, Missouri, have invented an Improvement in Valves, of which the following is a specification.

This invention relates to valves.

Among the several objects of the invention may be noted the provision of a simple and inexpensive construction of check or lift valve; and the provision of a device the parts of which are readily assembled and easily disassembled for inspection or repair. Other objects will be in part obvious and in part pointed out hereinafter.

The invention accordingly comprises the features of constructions, combinations of elements, and arrangements of parts, which are exemplified in the construction herein-after described and the scope of the application of which will be indicated in the following claims.

In the accompanying drawings, in which are shown two of various possible embodiments of this invention,

Fig. 1 is a central sectional elevation of one form of valve construction; and

Fig. 2 is a similar view of a modification.

Similar reference characters indicate corresponding parts throughout both views of the drawings.

Referring now more particularly to Fig. 1, there is illustrated at 1 a base or body having tapered threads at its upper end to receive a pipe (not shown), the same threads receiving an upper valve guide 3 having a central bearing in which the stem 5 of the upper valve 7 is slidably mounted. Standing lugs 9 on the guide facilitate insertion and removal of the guide. The threads that receive the valve guide 3 are not tapered.

In the central part of the body is mounted an annular member 11, preferably of brass. This is placed in the body with litharge, and is held tightly against the shoulder 13 by a ring 15 threaded in the lower part of the body. The ring is provided with spaced notches 26 to facilitate insertion and removal. The member 11 has seats for the upper valve 7 above mentioned and for the lower valve 17. The stem 19 of the latter

is slidably mounted in the valve guide 21, which comprises a central bearing 23 for the valve stem, an outer ring 25 apertured for the screws 27, and a web 29 connecting the bearing and the ring.

The screws 27 serve an additional function, of holding in place the bottom or base 31 and the screen or strainer 33. The screen is retained by the base, which in turn is held by the screws, tubular spacers 35 being provided around the screws to hold the base at the proper distance from the lower valve guide and to prevent the buckling of the screen, at the same time insuring retention of the screen in its proper position, on the surface 36.

A machine screw 37 is mounted in the lower valve 17, for a purpose hereinafter described.

In assembling the device the lower valve is small enough to pass through the upper aperture 39 in the valve seat 11, and the upper valve is small enough to pass through the upper threaded aperture in the body. Both valves may thus be inserted, if desired, after the seat is in place. The cotter pin 41 limits the upward travel of the lower valve when in service.

When the device is used in connection with a suction pump communicating with the pipe above mentioned, the device is preferably located at about the lowest level from which the pump is expected to draw liquid.

Assuming the suction line between pump and valve to contain air, the initial operation of the pump reduces the air pressure in the upper or discharge chamber 43, which allows the pressure in the middle or intermediate chamber 45 to open slightly the upper valve 7. This reduces the pressure in the middle chamber. Further operation of the pump causes further reduction in the middle chamber. This progressive reduction of pressure in the middle chamber causes lifting of the lower valve 17 and the drawing of air (if any) in the lower or inlet chamber 47 up into the middle chamber. When the air (if any) in the inlet chamber has been exhausted, and liquid flows there, the liquid is drawn up into the middle chamber, thence into the upper chamber and to the pump. During pumping, both valves are open wide. The

screw 37 permits lifting of the lower valve to a predetermined extent without causing the upper valve to lift.

The screen effectively prevents foreign matter from reaching the pump, and at the same time is located so close to the lowermost level of the device, that the pump is able to draw liquid down to almost the level of the bottom of the valve before air 10 can reach the pump and break the suction.

In the modification illustrated in Fig. 2, the lower valve is omitted. This construction suffices in many installations where the 15 double protection afforded by the two valves in Fig. 1 is not required.

In view of the above, it will be seen that the several objects of the invention are 20 achieved and other advantageous results attained.

As many changes could be made in carrying out the above constructions without departing from the scope of the invention, it is intended that all matter contained in the 25 above description or shown in the accompanying drawings shall be interpreted as illustrative and not in a limiting sense.

I claim:

1. In apparatus of the class described, in 30 combination, a body internally threaded at one end to receive a discharge pipe, an annular member seated in the body and having seats at its upper and lower ends for valves, a valve guide threaded on said 35 threads in the upper end of the body, an upper valve guided thereby and cooperating with the upper seat, means for holding said member in position against a shoulder in the body, a lower valve guide adjacent said 40 means, a lower valve guided thereby, a base held in position with respect to said body, and a screen or strainer mounted on the body and held in position thereon by a flange on the base.

45 2. In apparatus of the class described, in combination, a body, a member seated in the body and having seats for valves, valve guides in the upper and lower portions of the body, valves guided thereby and cooperating with the seats, a ring threaded in the lower portion of the body and holding said member in position against a shoulder in the body, tubular spacers registering with apertures in ring and lower guide, screws passing through said spacers and apertures and threaded into said ring, and a base held in position by said screws and spacers.

50 3. In apparatus of the class described, in combination, a body, an annular member seated in the body and having seats for valves, a valve guide threaded in the upper end of the body, an upper valve guided thereby and cooperating with the upper seat, a ring threaded in the lower portion of 55 the body and holding said member in po-

sition in the body, a lower valve guide adjacent said ring, a lower valve guided thereby and cooperating with the lower seat, a base or bottom plate held in position with respect to the body, an annular screen or strainer mounted on the body and held in position thereon by a flange on the base, and a lost-motion connection between the valve. 70

4. In apparatus of the class described, in combination, a body, a member seated therein and having seats for valves, valve guides in the upper and lower portions of the body, valves guided thereby and cooperating with the seats, means for holding said member in position in the body, a base held in position with respect to said body, a screen or strainer mounted on the body and held in position thereon by the base, and a lost-motion connection between the lower valve 75 and the upper valve. 80

5. In apparatus of the class described, in combination, a body taper-threaded at one end to receive a discharge pipe, an annular member seated in the body with litharge and having seats at its upper and lower ends for valves, a valve guide threaded on non-tapered threads in the upper end of the body, an upper valve guided thereby and cooperating with the upper seat, a ring threaded in the lower portion of the body and holding said member in position against a shoulder in the body, a lower valve guide adjacent said ring, a lower valve guided thereby and cooperating with the lower seat, tubular spacers registering with apertures in ring and lower guide, screws passing through said spacers and apertures and threaded into said ring, a base or bottom plate held into position by said screws and spacers, an annular screen or strainer mounted on a reduced end portion of the body and held in position thereon by a flange on the bottom plate, and a screw mounted on the lower valve and projecting toward the upper valve, said screw permitting limited motion of the lower valve independently of the lower valve, and upon the rising of the lower valve beyond such limit of motion, forcing the upper valve to rise. 90

6. In apparatus of the class described, in combination, a body internally taper-threaded at one end to receive a discharge pipe, an annular member seated in the body and having a seat for a valve, a ring holding said member in position in the body, a valve guide threaded on non-tapered threads in the upper part of the body, a valve guided thereby, a base held in position with respect to said body, and a screen or strainer mounted on the body and held in position thereon by the base, the chamber above the valve communicating directly with said pipe. 100

7. In apparatus of the class described, in 105

combination, a body adapted to receive a discharge pipe, a member seated in the body and having a seat for a valve, a ring threaded in the body and holding said member in position in the body, a valve guide threaded in the upper part of the body, a valve guided thereby and cooperating with the seat, screws threaded into said ring, a base held in position by said screws, and a screen or strainer mounted on the body and held in position thereon by the base.

8. In apparatus of the class described, in combination, a body internally threaded at one end, the end portion of the threads being tapered and the remainder non-tapered, the tapered portion being adapted to receive a discharge pipe, an annular member seated in the body and having a seat at its upper end for a valve, a ring threaded

in the lower portion of the body and holding said member in position against a shoulder in the body, a valve guide threaded on said non-tapered threads, a valve guided thereby and cooperating with the seat, tubular spacers registering with apertures in ring and guide, screws passing through said spacers and apertures and threaded into said ring, a base or bottom plate held in position by said screws and spacers, and an annular screen or strainer mounted on a reduced end portion of the body and held in position thereon by a flange on the bottom plate.

In testimony whereof, I have signed my name to this specification this 23rd day of February, 1922.

SHERWOOD HINDS.
